Primary Examiner — Mitchell Siegel(57) **CLAIM**

The ornamental design for a golf club grip, as shown and described.

DESCRIPTION

FIG. 1 is a top perspective view of a golf club grip; FIG. 2 is a bottom perspective view of the golf club grip of FIG. 1;

FIG. 3 is a front view of the golf club grip of FIG. 1;

FIG. 4 is a rear view of the golf club grip of FIG. 1;

FIG. 5 is a top view of the golf club grip of FIG. 1;

FIG. 6 is a bottom view of the golf club grip of FIG. 1;

FIG. 7 is a left view of the golf club grip of FIG. 1; and,

FIG. 8 is a right view of the golf club grip of FIG. 1.

The broken lines shown in one or more of the figures are for illustrative purposes only and form no part of the claimed design.
